UNITED STATES PATENT OFFICE.

JOHN P. LINTON, OF MONTREAL, QUEBEC, CANADA.

AUTOMATIC SPRINKLER.

1,319,230.

Specification of Letters Patent.

Patented Oct. 21, 1919.

Application filed October 22, 1917. Serial No. 197,894.

To all whom it may concern:

Be it known that I, JOHN P. LINTON, of the city of Montreal, Province of Quebec, Dominion of Canada, a subject of the King 5 of Great Britain, have invented certain new and useful Improvements in Automatic Sprinklers; and I do hereby declare that the following is a full, clear, and exact description thereof.

10 My invention relates particularly to thermo-disruptive automatic sprinkler heads by which a cap controlling the flow of water is held closed, and relates more particularly to the duck-bill type the members of which 15 have a disruptive tendency imparted thereto by the particular construction and arrangement of the parts which are held against disruption at ordinary atmospheric temperature by fusible solder adapted to run at 20 a predetermined temperature higher than usual atmospheric.

The object of my invention is to provide a thermo-disruptive member for an automatic sprinkler head of this type comprising 25 a pair of parts soldered together one of such parts being of such thickness to present necessary rigidity with an exposed side which is flat and smooth and the other part being relatively thin in order to permit rapid

30 penetration by abnormal heat, this thin member being of greater length than the rigid member and having its free end curved to present a lip in alignment with the flat smooth side of the thick member and a thin, 35 flat, uncut key soldered to the last mentioned side of the thick member and engaging the lip, the thick member affording facility for the key to fulcrum freely upon its end when the member is disrupted and thereby secure

40 an effective release of the parts. In order to increase the strength of the union between the two parts of the member at normal temperatures the contacting sides of the thin and thick members are corrugated to present 45 an extent of contacting surface greater than the distance between the ends thereof.

Another important feature of the invention consists in the specific construction and particular arrangement of the parts as above 50 mentioned and rendered instantaneous in their separation when disrupted by the specially disposed films and relatively greater masses of the solder. These specially disposed films and greater masses of solder do 55 not fuse uniformly owing to their different bulk, the heavier masses taking momentarily

longer. The effect is that all parts united by the solder films are released ready for separation and, in this condition, await the fusing and release of the relatively larger 60 masses. In this way, in the particular embodiment of my invention hereinafter specifically described, the key is held in place and is made to, in turn, hold all parts in place shutting off the water until the exact 65 instant when the larger masses are overcome by the heat and fuse. At this instant the head bursts and all the parts, both bills, key and cap are thrown clear of the nozzle.

For full comprehension, however, of my 70 invention, reference must be had to the accompanying drawings in which similar reference characters indicate the same parts, and wherein:

Fig. 1 is a side elevation of my improved 75 sprinkler head.

Fig. 2 is a vertical sectional view taken through the head on line 2—2 Fig. 1;

Fig. 3 is a similar view to Fig. 2 showing 80 the strut disrupted;

Figs. 4 and 5, 6 and 7 and 8 and 9 are detail plan views and end elevations respectively, of the top bill, bottom bill and key of my improved sprinkler head.

To facilitate connection with the water 85 pipe the nozzle 2 is externally screw-threaded as at 3 and the spring-yoke 4 is formed integrally therewith and has a hub 5 in which the screw-threaded stem 6 of a deflector 7 is screwed, while the mouth 8 of 90 the nozzle constitutes a valve-seat upon which the closing cap 9 is held under pressure exerted by the stem of the deflector and the disruptive strut, this pressure producing a tendency in the strut to disrupt. 95

This disruptive strut, according to my invention, comprises a pair of members presenting top and bottom bills 25 and 26 respectively, lying in contact with each other and having their contacting faces of transversely corrugated or saw-toothed longitudinal cross-section as at 27 thus presenting a bearing area of considerably greater dimensions than the distance in a straight line between the extremities of these faces. The 100 bottom member is comparatively thick to give strength to the joint whereas the top member is quite thin for the purpose of facilitating the penetration of the heat to the solder connection between the members 110 when a rise in temperature occurs. The bottom bill or member terminates at the end

of its corrugated face where it is cut off as at 10 to present a fulcrum shoulder 110 to be presently more particularly alluded to; while the end of the top bill or member is 5 projected and curved downwardly as at 28 and turned under to present a shallow lip 29 substantially in alinement with the under-face of the bottom bill. A key 30 is adapted to lie flat upon this under-face of 10 the bottom bill which is planed smooth for the purpose, and the key is of sufficient length to project beyond the shoulder 10 and engage the lip 29, while this underside has a pair of pits 31 with which engage a 15 pair of diminutive bosses 32 on the key.

The relation of these parts is such that when the key lies flat upon the underside of the bottom bill with its end in engagement with lip 29 the members of the strut 20 are in proper bearing relation. These parts are secured in this position by fusible solder with which a fusible joint is formed between the corrugated engaging faces; the space inclosed between the end of the bottom 25 bill, the curved end of the top bill and the end of the key is also filled with the solder; the opposite end of the key and the face bearing upon the bottom bill, and the face of the latter, are similarly joined with solder.

30 In order to increase the area and resultant holding power of the solder the corrugated or serrated portions of the bills are extended in width as shown in Figs. 4 and 6 and each bill is stiffened, the top bill owing to its 35 thinness by a rib 35 extending throughout the length thereof and around the turned-down end 28 and the bottom bill by a web 36.

The connection between the stem of the deflector and the valve cap is effected 40 through this strut by the inner ends of its members presenting inter-engaging off-centered compression devices by being provided with oppositely pointing feet 40 and 41 respectively, the heels of which are of ex- 45 tended width as at 42 and 43; and engage in pivotal relation by means of a rib 45 on heel 42 and groove 46 in heel 43 and serving as a seat for the rib. The portions of the members contiguous to these feet are recessed as 50 at 37 to jointly present an aperture 38 to give access to atmospheric heat to the inner end of the corrugated solder joint. The toes of these feet are in the form of conical 55 bosses 50 and 51 respectively, the apices being adapted to be seated in sockets 55 and 56 in the stem and cap 9, respectively.

The engaging rib 45 and seat 46 are off-set in the direction of the bills from the line of the apices 50 and 51 for the purpose of 60 causing pressure exerted on the points to be transmitted to the members of the strut and converted into a disruptive tendency.

To set my improved sprinkler head, the strut with its members and key soldered together, as described, is placed in position

with its points 50 and 51 in juxtaposition with the sockets 55 and 56, and the deflector 7 is turned until its stem compresses the feet of the strut sufficiently to impart necessary tension to the strut after which a locking 70 pin 60 is driven through the hub 5 of the spring-yoke into the stem 6.

When an abnormal temperature reaching the danger point acts upon the strut and while the film-like solder between the bills 75 and between the key and thick bill is first to run the greater mass of solder at 10 and at the opposite end of the key has the effect of holding all the parts until they are in perfect condition to separate. Immediately 80 the greater masses of solder are fused and run from the inclosure at the point 10 and from the opposite end of the key, the bills instantaneously open. Simultaneously with the first relative movement of the bills, in 85 an upward direction by the top bill and a downward direction by the bottom bill, the lip 29 presses upwardly on the end of the key causing it to fulcrum on the shoulder presented by the end of the bottom bill and the key is promptly thrown off. In this manner my improved strut is instantaneously 90 and completely disrupted, in other words all its parts bursts away from the nozzle immediately all the fusible solder runs.

The advantage of this construction over other sprinkler heads in use is that the increased area of the solder joint presented by the corrugated faces gives maximum holding strength and permits the top bill to be 100 very thin, while the particular arrangement of the lipped overhanging top bill and the sharp and comparatively deep fulcrum shoulder 110, presented by the sheared-off end of the bottom bill exerts considerable 105 leverage on the key, which, when the solder is fused thereby pries off the key and makes its release and throw-off absolutely certain. Another advantage of this particular arrangement of parts is that practically the 110 entire key is subject to the heat of any fire it is the intention to extinguish through the medium of this sprinkler head owing to the fact that the key is practically entirely on the underside of the bills.

115 Another advantage of my particular combination of bills and key is that the disruptive load exerted by the compressive forces in the head is almost altogether relieved from the solder joint uniting the bills and taken up by the key.

What I claim is as follows:—

1. In a sprinkler head the combination with a yoke, a nozzle, a cap closing the nozzle and pressure means carried by the yoke 125 in axial alinement with the nozzle, of a disruptive strut, having a relatively long horizontal member consisting of a thin top bill with downwardly curved lip at one end and a relatively massive bottom bill having a 130

flat smooth underside constituting a solder face such bills having integral comparatively short interengaging parts presenting solder faces of relatively increased area; a 5 thin flat uncut key lying in contact with the flat smooth underside of the relatively massive bill and projecting beyond one end thereof into engagement with the lip.

2. In a sprinkler head the combination 10 with a yoke, a nozzle, a cap closing the nozzle, and pressure means carried by the yoke in axial alinement with the nozzle, of a disruptive strut, having a relatively long horizontal member consisting of a thin top bill 15 with downwardly curved lip at one end and a relatively massive bottom bill having a flat smooth underside constituting a solder face such bills having integral comparatively short interengaging parts presenting solder faces 20 of relatively increased area; a thin flat uncut key lying in contact with the flat smooth underside of the relatively massive bill and projecting beyond one end thereof into engagement with the lip; films 25 of solder joining together the solder faces of the bills and the key to the bottom bill, and relatively greater masses of solder joining the ends of the key in place.

3. In a sprinkler head the combination 30 with a yoke, a nozzle, a cap closing the nozzle and pressure means carried by the yoke in axial alinement with the nozzle, of a disruptive strut, having a relatively long horizontal member consisting of a thin top bill 35 with downwardly curved lip at one end and a relatively massive bottom bill having a flat smooth underside constituting a solder face, such bills having integral comparatively short interengaging parts presenting solder 40 faces of relatively increased area; a thin flat uncut key lying in contact with the flat smooth underside of the relatively massive bill and projecting beyond one end thereof

into engagement with the lip, the bills having oppositely pointing feet with pointed toes seated in the cap and pressure means, and heels offset relatively to the axial plane of the pointed toes, the heels being of relatively diminutive width in the direction of the bills substantially as described and for 50 the purpose set forth.

4. In a sprinkler head the combination 55 with a yoke, a nozzle, a cap closing the nozzle and pressure means carried by the yoke in axial alinement with the nozzle, of a disruptive strut, having a relatively long horizontal member consisting of a thin top bill with downwardly curved lip at one end and a relatively massive bottom bill having a flat smooth solder face on its underside such 60 bills having integral comparatively short interengaging parts presenting solder faces of relatively increased area, a thin flat uncut key lying in contact with the flat smooth underside of the relatively massive bill and 65 projecting beyond one end thereof into engagement with the lip; films of solder joining together the solder faces of the bills and the key to the bottom bill, and relatively greater masses of solder joining the ends of the key 70 in place; the bills having oppositely pointing feet with pointed toes seated in the cap and pressure means and heels offset relatively to the axial plane of the pointed toes, the heels being of relatively diminutive 75 width in the direction of the bills substantially as described and for the purposes set forth.

In testimony whereof I have signed my name to this specification in the presence of 80 two witnesses.

JOHN P. LINTON.
